UNITED STATES PATENT OFFICE.

MARY AUGUSTA HAWLEY, OF DIXON, ILLINOIS.

AUTOMATIC POULTRY-DUSTING DEVICE.

No. 829,207.

Specification of Letters Patent.

Patented Aug. 21, 1906.

Application filed March 20, 1905. Renewed April 21, 1906. Serial No. 312,974.

To all whom it may concern:

Be it known that I, MARY AUGUSTA HAWLEY, a citizen of the United States of America, and a resident of Dixon, Illinois, have invented certain new and useful Improvements in Automatic Poultry-Dusting Devices, of which the following is a specification.

This invention relates to apparatus for applying vermin-destroying powder to fowls; and it comprises certain novel devices and arrangements thereof, with means actuating the same, whereby fowls in passing into and out of a hen-house are sprinkled with such powder. This application includes certain improvements to the apparatus, the subject of Letters Patents No. 472,456 of April 5, 1892, and No. 507,615 of October 31, 1893, both issued in my name.

The object of the present invention is to provide means whereby the powder to be sprinkled over the fowls may be mechanically agitated within its container, and thereby more positively caused to percolate through its perforated base and descend over the passing fowls in the operation of the device.

In the drawings accompanying this application, Figure 1 is a perspective elevation of my improved apparatus. Fig. 2 is a detail view of the concussion device, and Fig. 3 is a detail view of the powder-container.

In the figures the letter A indicates the base of my apparatus, from opposite sides of which extend uprights A' A', which uprights are contracted toward their upper ends, as at 35 a a, and there adapted to receive and support a powder-container, as B, which has a perforated base b. The contracted portion of one of the uprights has an offset portion a', to which is pivoted a double-arm lever, as 40 B', one arm of which has a weight, as a², normally resting upon the offset a', while the other arm, which is provided with a striker a³, is normally in a pendent position. A platform, as C, is pivotally mounted upon the 45 base A, as from brackets c c, while at a point distant from the fulcrum thus provided said platform is supported by a rod c', which is connected at its lower end to said platform and at its opposite end is connected with said 50 double-arm lever, being engaged with an extension a⁴, protruding from said lever at a point intermediate the arms thereof. A push-rod D is slidably supported in a hori-

zontal position through the container B, said rod supporting interiorly of the container an 55 agitator E. This agitator consists of a plate having pendent teeth e, located at a point near the perforated base of the container. The rod D protrudes exteriorly of the container, having a head d located in the path of 60 the striker a³ to be actuated thereby. A coiled spring d' holds the rod D with its head d normally extended, as seen.

In the operation of my invention the apparatus being installed within the usual opening in a hen-house through which the fowls pass in entering and leaving the house, the fowls are compelled to step upon the oscillatory platform C in passing to and fro, as is obvious. The weight of the fowl being imposed upon said platform causes it to rock upon its fulcrum, thereby drawing downwardly the rod c', in which action the double-arm lever B' is swung in such manner that the striker a³ strikes the head d, giving an impulse to the push-rod D, causing the agitator E to move across the base of the container B, moving the powder and causing it to percolate through the perforated base and fall upon the fowl. The weight a² in this action 80 has been elevated above the offset a'. As the fowl prepares to leave the platform C the latter resumes its normal position through the counterbalancing action of the weight a², which latter descending suddenly upon the 85 offset a', the impact thereof shaking the container-support, while at the same time the spring d' in relaxing moves the push-rod D outwardly, again causing the agitator E to disturb the powder. The sprinkling operation is of course assisted through the vibratory action of the container set up by the impact of the weight a² upon the offset a'. Thus the fowl in passing over the platform C is twice sprinkled in a positive and efficient 90 manner with insect-killing powder.

Having described my invention, I declare that what I claim is—

A fowl-dusting device comprising a base, a pair of standards extending therefrom, an 100 offset arm on one of said standards, a powder-container supported by said standards, a flat, perforated base for said container, an oscillatory platform pivoted upon the base of the apparatus, a powder-agitator within 105 said container, said agitator comprising a

plate having pendent teeth adapted to reciprocate across the perforated base, a spring-held rod to support and actuate said agitator, and a double-arm lever pivoted to said offset 5 arm and carrying a striker for said push-rod and a counterbalancing-weight for said platform, said counterbalancing-weight being adapted to strike said offset arm to shake the

container, together with a rod connecting said platform and double-arm lever.

Signed at Dixon, Illinois, this 8th day of March, 1905.

MARY AUGUSTA HAWLEY.
